AUTOMOBILE WINDOW SASH AND SCREEN
ASSEMBLYBernard A. Lange, Brantwood, Wis., assignor of
one-half to Everette Steele, Brantwood, Wis.

Application February 14, 1952, Serial No. 271,530

1 Claim. (Cl. 296—44)

1

This invention appertains to automobiles and more particularly to a novel window construction therefor.

One of the primary objects of this invention, is to provide means for incorporating a sliding window screen in an automobile door or the like, with means for raising and lowering the screen from the inside of the automobile, so that upon the lowering of the sash glass for ventilation entrance of insects into the body of the automobile will be prevented as well as the entrance of unauthorized persons during parking and the like.

Another salient object of the invention is the provision of novel means for operating the sash glass and the window screen and for incorporating such operating means in an automobile door in such a manner that a compact and durable construction will be had, and whereby the operating means for the screen will not interfere with the operating means for the glass.

A further object of the invention is to provide means for operating the sash glass and the screen from one side of the door with novel anti-friction rollers on the other side of the door for engaging the glass and screen, so that binding of the glass and screen in their guide channels is prevented, and whereby easy raising and lowering of the glass and screen is assured.

With these and other objects in view, the invention consists in the novel construction, arrangement and formation of parts, as will be hereinafter more specifically described and claimed and illustrated in the accompanying drawing, in which drawing,

Figure 1 is an elevational view of the inner side of an automobile door, parts of the view being shown broken away and in section, to illustrate structural detail.

Figure 2 is an enlarged horizontal sectional view taken on the line 2—2 of Figure 1, looking in the direction of the arrows illustrating a part of the operating mechanism for the glass sash and the window screen and the roller guides therefor.

Figure 3 is a fragmentary vertical sectional view through the door taken on the line 3—3 of Figure 2, looking in the direction of the arrows illustrating the operating means for the sash glass.

Figure 4 is a view similar to Figure 3, but taken on the line 4—4 of Figure 2, looking in the direction of the arrows and illustrating the operating means for the screen.

Figure 5 is a fragmentary detail horizontal sectional view taken on the line 5—5 of Figure 4, looking in the direction of the arrows.

2

Referring to the drawing in detail, wherein similar reference characters designate corresponding parts throughout the several views, the letter D indicates a door of the general construction now commonly found in automobiles. The door D, however, includes certain novel features, as will be later set forth. As illustrated, the door is of a hollow construction having a window opening 10 and a well or pocket 11 for receiving the sash glass 12, when the glass is in a lowered position.

In accordance with the invention, I also provide a sliding screen 13 for the window opening 10, whereby the opening is adequately protected when the glass 12 is in a lowered position for ventilation. The opposite sides of the window opening are provided with stiles 14 and 15 which extend down into the well 11. The stiles 14 and 15 are each provided with vertical channels 16 and 17 for guiding respectively, the glass 12 and the screen 13, during the raising and lowering thereof. Stops 18 can be arranged in the channels for limiting the downward movement of the sash glass 12 and the screen 13. One of the important features of the invention, as heretofore set forth is the provision of a novel operating means for the sash glass and a novel operating means for the screen, so that such operating means can be easily incorporated within an automobile door and so that the two operating means will not interfere one with the other. The operating means for the sash glass 12 includes a vertically extending rack bar 19 fastened to one vertical edge of the glass, and it is to be noted that this rack bar 19 extends a distance below the lower edge of the glass. The rack bar 19 can be fastened to the glass 12 in different manners, but I prefer to utilize a fastening strip 20 of a substantially H-shape in cross-section. One vertical edge of the glass is pressed into one side of the strip and is suitably padded by a rubber cushion 21, and the glass can be secured to the cushion by an adhesive and the cushion in turn, if such should be desired, can be adhesively connected to the strip. The outer side of the strip receives the rack bar 19 and countersunk rivets 22 can be utilized for rigidly securing the rack bar at spaced points to the strip. Just below the window opening 10 and at one side thereof, the door rotatably carries a shaft 23 and the opposite panels of the door can carry suitable bearings for this shaft. The inner end of the shaft protrudes through the inner face of the door and has secured thereto an operating crank 24, whereby the shaft can be rotated. Keyed, or otherwise fastened, to the shaft within the hollow

door is a spur gear or pinion 25, which meshes with the teeth of the rack bar, and it is to be noted that the wall of the channel 16 of the stile 14, is slotted so that the gear or pinion 25 can project into the channel 16 for meshing engagement with the rack. Obviously, by turning the crank 24, the glass 12 can be raised or lowered.

Now, referring to the screen 13, the same is preferably woven from copper or brass wire to form a fine mesh so as to prevent the entrance of insects into the automobile when the screen is in a raised position and the sash glass in a lowered position. The wire mesh is protected by a marginal reinforcement and this preferably includes inner and outer companion open frames 26 and 27 which receive the woven wire therebetween. The wire and frames are firmly united by countersunk rivets 28, and these frames on one side receive therebetween a vertically extending rack bar 29 and the rivets 28 secure the rack bar 29 in place. Attention is also directed to the fact that the rack bar 29 extends below the lower edge of the screen 13. The rack bar 29 is preferably of a T-shape in cross-section, as is best shown in Figures 2 and 5. This rack bar forms a part of the operating mechanism for the screen 13. To operate the screen 13 without interfering with the operating mechanism for the sash glass, I provide an operating pinion or gear 30, which meshes with the teeth of the rack bar 29. The channel 17 of the stile 14 is slotted to permit this gear or pinion 30 to extend into the channel for engaging the rack bar. The gear or pinion is keyed to a rotatable shaft 31 mounted in suitable bearings formed on the inner faces of the inner and outer panels of the door. Below the shaft 31 and at one side thereof is an operating shaft 32 and this shaft is also mounted in suitable bearings carried by the door and the shaft extends through the inner face of the door and has securely fastened thereto an operating crank 33. A train of gearing 34 operatively connects the shaft 32 with the pinion or gear 30, and as illustrated, I provide two spaced idle shafts 35 and 36 between the shafts 31 and 32. The shafts 35 and 36 are mounted in bearings carried by the door. Keyed, or otherwise fastened to the shaft 32, is an operating spur gear 37, and this spur gear meshes with a gear 38 on the shaft 36. The gear 38 in turn meshes with a gear 39 on shaft 35 and this gear meshes with the operating gear or pinion 30 for the rack bar 29. It is to be noted that the shafts 32, 35 and 36 are in vertical alignment while the shaft 31 is at one side of the shafts. By providing the train of gearing 34, the operating crank 33 is disposed a sufficient distance from the operating crank 24 so that one crank will not interfere with the other.

As the sash glass 12 and the screen 13 are operated from one side thereof, there might be a tendency for the sash glass and screen to tilt and bind in their channels. To eliminate this, I arrange in the stile 15, a plurality of spaced shafts 40 carrying rubber rollers 41. As best shown in Figure 2, there are two rollers on each shaft and the channels 16 and 17 of the stile 15

are slotted so that the rollers 41 can project into the channels 16 and 17 for engaging the vertical edges of the glass 12 and the screen 13 opposite to the vertical edges carrying the rack bars 19 and 29.

From the foregoing description, it can be seen that I have provided an effective means of a compact order for raising and lowering a sash glass and a screen for the window opening of an automobile door.

The channels for the glass and screen may be provided with felt weather resistant guides, if such should be desired.

Changes in details may be made without departing from the spirit or the scope of this invention, but what I claim as new is:

In an automobile door having a window opening therein and a well below the opening, side stiles for the window opening extending into the well, each having spaced guide channels, a sash glass and a screen slidably mounted in the channels and movable into the well to an open position and into the window opening in their closed position, the glass and the screen each having a vertical rack bar secured to one edge thereof on the same side of the window, said channels on the other side of the window each having a series of vertically spaced aligned slots therein, a series of spaced rotatably mounted transverse shafts carried by the door, each shaft positioned behind a pair of the horizontally aligned slots, anti-friction rollers secured to each shaft on the other side of the window extending into a respective slot and engaging the edges of the glass and screen opposite to the edges carrying the rack bars, said window guide channel having a slot therein on the side opposite the vertically spaced slots, an operating shaft carried by the door having a pinion extending into said last mentioned slot and meshing with the rack bar for the glass, an operating crank for the shaft arranged on the inside of the door, an operating shaft rotatably carried by the door disposed a considerable distance below the first operating shaft, an operating crank therefor, said screen guide channel having a slot on the side opposite the vertically spaced slots and positioned below the last mentioned window channel slot, an actuating shaft carried by the door disposed between the mentioned operating shafts having a pinion extending into the screen channel slot and engaging the rack for the screen, and a train of gearing operatively connecting the second mentioned operating shaft with the pinion of the actuating shaft.

BERNARD A. LANGE.
